UNITED STATES PATENT OFFICE.

THEODORE R. TIMBY, OF BROOKLYN, NEW YORK.

MECHANISM FOR UTILIZING WIND-POWER.

SPECIFICATION forming part of Letters Patent No. 741,389, dated October 13, 1903.

Application filed April 24, 1903. Serial No. 154,096. (No model.)

To all whom it may concern:

Be it known that I, THEODORE R. TIMBY, a citizen of the United States, residing at Brooklyn, in the county of Kings and State of New York, have invented certain new and useful Improvements in Mechanism for Utilizing Wind-Power, of which the following is a specification.

This invention relates to mechanism for utilizing and storing the power of the wind and making it available for mechanical purposes.

The object of the invention is to utilize wind-wheels for the compression of air which is stored for mechanical use and to utilize the storage vessels as supports for the wind-wheels, also to supply an auxiliary apparatus by which the weight of a body may be lifted by the wind-wheels, and when lifted the weight may be automatically thrown into operation to assist in compressing air to reinforce a failing supply.

The invention consists in certain mechanisms and combinations, as hereinafter claimed.

Figure 1 is an elevation of an apparatus illustrating the principles of my invention, one of the storage towers or tubes being shown in section and showing the auxiliary weight mechanism. Fig. 2 is a section of the mechanism for throwing the weight into operation.

Let 1 indicate a strong tube of metal firmly anchored in the ground and projecting far enough above ground to clear obstructions, so as to give a fair sweep to the wind.

2 2 indicate supports for wind-wheels, and 3 3 are the wheels thereon. These wheels are of any usual construction and are provided with any usual means for keeping the wheels 40 faced in operative relation to the wind. The wheels are connected in usual manner to air-compressors 4, and these compressors condense air and force it into the interior of a tube 1 through pipes 5. The return of the 45 air is prevented by a check-valve in manner well known. The tube 1 is air-tight, and this tube constitutes a storage-chamber for the compressed air. Where several tubes or towers 1 1, &c., are arranged in series they may 50 be connected by pipes, as 6, and suitable cut-offs or cocks 7 may be provided, so as to retain the compressed air when stored. Com-

pressed air is drawn from any of the storage tubes or towers by suitable connections, as from plugs 8. As the wind is liable to blow 55 day and night and power in the form of compressed air can be stored at night and utilized in the day, it is only necessary to maintain the machines in operative condition to be reasonably sure of a storage of power from 60 the force of the wind, which will be available when the wind does not blow.

One or more of the wind-wheels 3 may be utilized to turn a windlass 12, by which windlass a heavy weight 13 may be lifted, the 65 weight being suspended, preferably, inside one of the towers or tubes 1. When the air-pressure in the tower runs below a predetermined minimum, the reduction of pressure acts automatically to trip a catch and let the 70 weight run down. The falling weight operates the windlass to drive an air-compressor 15, and this compressor forces more air into the storage tube or reservoir 1. The storage-tubes will be provided with safety-valves, if 75 desirable, or such valves can be fixed in the service-pipes.

A mechanism which may be used to start the weight into operation when the pressure falls in tube 1 is shown in Fig. 2. Let a pipe 80 18 be connected to tube 1 and let an enlargement 19 of this pipe 18 be closed by a flexible diaphragm 20. Said diaphragm is connected by a weighted link 21 to a pawl 22, which pawl is in position to engage teeth on 85 a ratchet-wheel 23 on shaft 17 of the windlass. The falling pressure in the tube 1 allows diaphragm 20 to fall, under influence of weight W, and the pawl is released from the ratchet, permitting the windlass to come in 90 operation to drive the air-compressor 15. An increase of pressure in tube 1 tends to lift the diaphragm, thus again engaging the ratchet 22 with pawl 23 and stopping the fall of the weight. The gearing and clutches 95 necessary to drive the wind-wheel, so that the power of the driving wind-wheel will be utilized, will be readily supplied by a skilled mechanic and is no necessary part of the present invention.

The towers formed by the storage-tubes may be arranged in groups, as shown, or otherwise. Any convenient number of wind-motors may be arranged on each tower or reser-

voir. A wind-motor may be connected to the weight, so as to operate either to raise the weight or to drive an air-compressor, as will be understood by any mechanic skilled in this art.

What I claim is—

1. In a mechanism for utilizing wind-power, a storage-reservoir, a wind-wheel mounted thereon, an air-compressor driven by the wind-wheel and connected to the storage-reservoir to compress air into the same, a second wind-wheel and a weight-lifting mechanism connected thereto, and means by which the falling of the weight actuates a second air-compressor to reinforce the first.

2. In mechanism for utilizing wind-power, an air-compressor driven by a wind-motor, a storage-reservoir for the air so compressed, a weight and means for lifting the same device by the air-motor, and mechanism for auto-

matically utilizing the power of the weight as the air-pressure falls in the reservoir.

3. In mechanism for utilizing wind-power, a hollow cylindrical metallic tube, anchored in the ground, and constituting the tower of a wind-wheel, a wind-wheel mounted on said tower, an air-compressor driven by said wind-wheel, connections from said air-compressor to the interior of the tube, so that the compressed air is stored in the tube, auxiliary means within the tube by which a second air-compressor is operated to reinforce the first, combined with the second air-compressor, substantially as described.

In testimony whereof I affix my signature in presence of two witnesses.

THEODORE R. TIMBY.
